UNITED STATES PATENT OFFICE.

FRANCIS BELL REILLY, OF REGINA, SASKATCHEWAN, CANADA.

BUILDING CONSTRUCTION.

Original application filed August 15, 1921, Serial No. 492,594. Divided and this application filed August 26, 1922. Serial No. 584,513.

To all whom it may concern:

Be it known that I, FRANCIS BELL REILLY, of the city of Regina, in the Province of Saskatchewan, Dominion of Canada, have

5 invented certain new and useful Improvements in Building Constructions, of which the following is a specification.

This invention relates to improvements in concrete buildings and the objects of the 10 invention are to enable a building of this character to be more readily and more economically constructed without impairing the strength thereof.

Further objects are to enable a building 15 of this character to be constructed without the erection of special forms for the walls or flooring of the building. Further objects still are generally to improve and simplify 20 the construction of the various sections and blocks entering into the concrete building and to better adapt them to perform the various functions required of them, and it consists essentially of the improved construction hereinafter described in detail in 25 the accompanying specification and drawings.

In the drawings:

Figure 1 is a cross sectional view of one of the wall blocks.

30 Figure 2 is a cross sectional view of a plurality of the wall blocks in position.

Figure 3 is a cross section through one of the floor blocks.

35 Figure 4 is a cross sectional view showing a plurality of the floor blocks in position.

Figure 5 is a face view of the block for the window frame.

40 Figure 6 is a side view of the block shown in Figure 1.

Figure 7 is a cross sectional view through the block forming the window jamb.

Figure 8 is a cross sectional view through the block forming the door jamb.

45 Figure 9 is a side view of the block in the window jamb.

Figure 10 is a detail partially in section showing the manner of attaching the hinge to the door jamb.

50 Figure 11 is a cross sectional view of the roof slabs.

Figure 12 is a sectional elevation of a building constructed in accordance with the present invention.

55 This application is a divisional of my

earlier application filed August 15th, 1921, under Serial No. 492,594 which matured into a Patent No. 1,445,713, date February 20, 1923.

In constructing the building in accordance with the present invention, the walls are formed from a plurality of concrete blocks preferably reinforced and they are manufactured away from the building and are preferably of uniform size. These 60 blocks are united by connecting columns which are poured on the job and are designed to support flooring slabs on which the floor is supported, the window and door jambs being also cast away from the job 65 and placed in position as hereinafter described.

Referring particularly to Figures 1 and 6 which show the side block, it will be seen that it comprises a cross section of a block 75 in which the inner wall *a* and outer wall *b* are held in place by cross webs *d* and *d* to which a center wall *c* is attached, thus forming two air spaces *e* and *f* which extend from top to bottom of the block, which 80 block extends from floor to ceiling, as shown in Figure 12.

These blocks are reinforced with rods, expanded metal, wire mesh or other suitable reinforcing material. Where lightness is 85 desired the center wall *c* may be of sheet metal or fibre board, or other prepared material which is cast in place at the time the block is made. Extending upwards from the webs *d*, *d*, is a metal loop *h*, Figure 6, 90 by which the block is lifted in a crane or other hoisting apparatus.

It will be seen that when the blocks are set in place in the wall there will be a space between the adjacent cross webs *d* and in 95 these spaces concrete columns *g* are poured, these being reinforced with suitable rods which are wired apart and dropped into place before the column is cast. A tapered core *h* is set in place before the column is 100 cast and when concrete is set this is withdrawn leaving an air space *i* between the column *g* and the inner wall *a*. A little mortar is poured down spaces *e* and *f* forming an effectual stop at *l*. The webs *d* and 105 center wall *c* are kept shorter than the outer walls *a* and *b*. The top of air spaces *e* and *f* are covered or stopped as at *m*, thus making the form in which the beam *n* is cast, which is also suitably reinforced. 110

The beams *n* carried up to top of wall *a* form supports on which the floor or ceiling is carried.

As shown in Figure 3, the floor tile is pre-casted in lengths to reach from beam to beam and the sides of which, *o*, *o*, are set on slope to form a dove-tail to support the tiles after the floor is run. These concrete tiles are also reinforced sufficiently to enable them to be handled and put into place.

Figure 4 shows a cross section of the floor; the tiles being placed side by side. The rods to reinforce the floor beams are set in place and the beams *p*, *p* are poured along with the concrete floor *r* on which wood flooring or other selected floor covering is laid in the usual manner.

The outer wall *b* of the block extends to the top of the floor *r* as shown in Figure 12 thus enabling the floor to be continued to the outer wall, thus forming a base on which the blocks for the story above are placed. Where it is desired to carry the floor or ceiling out to form a cornice, the walls *a* and *b* are left the same height and the floor tiles are extended over the beam end as shown in upper part of Figure 12. This cornice forms the outer support of the roof slabs *s*, of which a cross section is shown in Figure 11. On these a plastic or felt roofing is laid.

Figure 5 shows a face view of a block into which a window frame is placed. A section of the jamb and block at *t*, *t* is shown in Figure 7. *u* is a pressed metal jamb having molded blind stop at 1 and rebate for parting stop at 2, a window stop at 3. The metal is embedded in the concrete and the ordinary double hung window sashes are used.

Figure 9 shows a vertical section of the jamb at *x*—*x*, Figure 7, in which a pocket 7 is placed to receive a spring sash balance.

Figure 8 shows a door jamb made in a similar manner.

Figure 10 shows how a metal plate is embedded in the concrete having threaded holes into which bolts through the hinge are fastened.

In constructing the building it will be necessary to support the floor tiles and blocks constituting the side walls in place until the concrete frame formed by the various beams and floors are set. Any suitable form of frame may be used for this purpose.

The interior walls and ceilings can be plastered directly on the block owing to the double air space without the use of lath, but if a further insulation is required the interior wall *a* can be made of any convenient insulation plaster. The external walls may be rough cast directly on the blocks or merely treated at joints.

The wall block shown is of rectangular shape, but in the case of a building with a round or curved wall, the inner and outer walls of the blocks will be shaped to conform with the shape of the building.

As many changes could be made in the above construction and many apparently widely different embodiments of my invention, within the scope of the claims, constructed without departing from the spirit or scope thereof, it is intended that all matter contained in the accompanying specifications and drawings shall be interpreted as illustrative and not in a limiting sense.

What I claim as my invention is:

1. A building construction comprising a plurality of wall blocks having recesses in their ends designed when the blocks are set together to form spaces to receive a vertically extending column, a plurality of columns cast in said spaces; certain of the wall blocks having their outer walls projected above the inner walls to form a seat on the inner wall, a floor supported on the seat comprising a plurality of tiles, slabs and a concrete floor interlocked with the slabs.

2. The construction as claimed in claim 1 in which the floor tiles are formed with dove-tailed center portions interlocking with a poured concrete flooring.

3. A concrete construction comprising a plurality of wall tiles set adjacent to each other and one above another, the said wall tiles having vertically extending passageways and having side recesses forming spaces to receive partially extending columns, columns cast in the said spaces, connecting beams for said columns, means for stopping the openings at the top and bottom of each block and a flooring supported on the columns and connecting beams.

In witness whereof I have hereunto set my hand in the presence of two witnesses.

FRANCIS BELL REILLY.

Witnesses:

V. L. WILLIAMS,
A. M. KRONBERGER.
